MODULAR MOBILE HOME WITH OFF-CENTER ROOF PEAK

Dan Philip Eacret, Fountain Valley, Calif., assignor to
Bendix Home Systems, Inc., Atlanta, Ga.

Filed July 17, 1972, Ser. No. 272,475

Term of patent 14 years

Int. Cl. D25—03

U.S. Cl. D13—1 A

Fig. 2

Fig. 3

Fig. 4

Fig. 5

FIG. 1 is an exploded perspective view of a modular mobile home with off-center roof peak; and

FIGS. 2-5 are left side, right side, front and rear elevational views, respectively, of the assembly mobile home illustrated in FIG. 1.

I claim:

The ornamental design for a modular mobile home with off-center roof peak, as shown.
